APPARATUS FOR HANDLING STRANDS

Julius A. Wagner, Cleveland Heights, Ohio, assignor to Western Electric Company, Incorporated, New York, N. Y., a corporation of New York

Application July 14, 1944, Serial No. 544,942

4 Claims. (Cl. 66—163)

This invention relates to apparatus for handling strands and more particularly to safety devices for strand handling apparatus.

In knitting a plurality of strands into textile coverings for conductors, occasionally one of the strands breaks, and unless the knitting machine is stopped, the covering subsequently applied to the conductor on which the covering is knitted will be imperfectly formed.

An object of the invention is to provide new and improved apparatus for handling strands.

One device embodying the invention comprises a holder for a strand supply, means for advancing a strand from the strand supply holder, and means for stopping the advancing means comprising means for deenergizing the apparatus, a cam for actuating the deenergizing means, an oscillating member, and means normally engaging a strand being advanced for connecting the cam with said oscillating means to actuate the deenergizing means whenever the tension on said strand is less than a predetermined amount.

A clear understanding of the invention may be obtained from the following detailed description of one embodiment thereof, when read in conjunction with the appended drawings, in which

Fig. 1 is a vertical fragmentary elevation, in partial section, of an apparatus embodying the invention;

Fig. 2 is a horizontal sectional view of the apparatus taken along line 2—2 of Fig. 1;

Fig. 3 is a horizontal sectional view of the apparatus taken along line 3—3 of Fig. 1, and

Fig. 4 is a horizontal sectional view of the apparatus taken along line 4—4 of Fig. 1.

Referring now to the drawings, a knitting head 10 (Fig. 1) forming a part of a conventional type of a knitting machine (not shown) is driven by suitable driving means (not shown) well known to the art of knitting, as is the rest of the knitting machine. The driving means also rotates a shaft 12 (Fig. 4) having a rotary disc 15 secured thereto. One end of a link 16 secured to an arm 17 formed on a disc 19 is connected eccentrically to the disc 15 by a pin 20. Thus, when the knitting machine is driven, the disc 19 is oscillated by the link 16, which is reciprocated by the disc 15. The disc 19 is rotatably secured upon a hollow shaft 22 (Figs. 1 and 4) which is rotatably mounted in a vertical bearing 24 in alignment with the knitting head 10. A plurality of notches 25—25 provided in the periphery of the disc 19 are spaced equally therearound.

A cam 26 having lobes 27—27 (Fig. 2) is secured to the upper end of the shaft 22. If the

cam 26 is rotated in either direction, one of the lobes 27—27 strikes a spring-pressed button 28 of a microswitch 29, whereby the normally closed contacts of the microswitch, which contacts connect a pair of insulated conductors 34—34, are opened to stop the driving means (not shown) of the apparatus.

A collar 30 (Fig. 3) formed on the shaft 22 is provided with a plurality of slots 31—31 spaced around the periphery thereof. Each of a plurality of L-shaped levers 32—32 is pivotally mounted in one of the slots 31—31 and one of a plurality of grooved rollers 35—35 is mounted on one of the ends of each of the levers 32—32. The rollers 35—35 are designed to engage strands 36—36 which are drawn by the knitting head 10 from a plurality of cops such as a cop 37 (Fig. 1), which are mounted around the knitting head 10 in spaced relationship. A plurality of conventional braking discs 39—39 serve to tension the strands 36—36 as the strands pass under the rollers 35—35 to the knitting head 10, whereby the lower ends of the levers 32—32, as viewed in Fig. 1, are held away from the disc 19 and the shaft 22 is held against rotation with respect to the bearing 24.

When the knitting machine is energized, the knitting head 10 (Fig. 1) knits the strands 36—36 into a covering 40 upon a conductor 41 which is advanced through the shaft 22 and the knitting head 10 by a capstan 42 driven by the driving means (not shown).

In the operation of the apparatus described hereinabove, the driving means is actuated to drive the knitting head 10, the capstan 42 and the shaft 12, whereby the conductor 41 is advanced through the knitting head, the covering 40 is formed on the conductor as the conductor is drawn through the knitting head, and the disc 19 is oscillated with respect to the shaft 22. As long as all of the strands 36—36 are continuous between the braking discs 35—35 and the knitting head 10, the shaft 22 is held stationary with respect to the bearing 24 by the tensioned strands 36—36, which, at this time, also hold the levers 32—32 out of the notches 25—25.

If any of the strands 36—36 breaks or any of the cops, such as the cop 37 becomes exhausted, that strand will be drawn from between the braking discs 39—39, and the outer end of that one of the levers 32—32, previously supported thereby, will fall. When one of the levers 32—32 falls, the lower end thereof, as viewed in Fig. 1, will be urged into one of the notches 25—25 as the notch is moved opposite thereto. As the le-

ver 32 enters the notch 28 and the disc 18 is rotated, the shaft 22 will be carried therewith and one of the lobes 27-27 will strike the spring-pressed button 28 to open the contacts of the microswitch 29, whereby the driving means will be stopped and the knitting machine, the capstan and the shaft 12 will come to a stop. The operator may then splice the broken strand 36, if it has been broken, or replace an exhausted cop if that is the trouble, and the operation then may be continued.

The apparatus described hereinabove prevents the continuation of a knitting operation whenever a strand 36 is broken or exhausted and accomplishes this result with only a single microswitch regardless of the number of the strands 36-36 being formed into the covering.

What is claimed is:

1. In a strand supplying apparatus, a holder for a strand supply, means for advancing a strand from said holder, and means for stopping the advancing means, comprising a switch for deenergizing the advancing means, a cam, an oscillating means, and a member pivotally mounted on said cam with one end thereof normally held in a raised position by a strand being advanced from said holder for positively connecting said oscillating means to said cam to actuate said switch whenever said strand fails to support the end of said member.

2. In a strand supplying apparatus, a holder for a strand supply, means for advancing a strand from said holder, and means for stopping said advancing means, comprising a microswitch for stopping the advancing means when the contacts thereof are opened, a cam having a lobe formed thereon for opening the contacts of said microswitch, a disc having notches formed in the periphery thereof and mounted for rotation about the axis of the cam, means for oscillating said disc about the axis of the cam, and a lever pivotally secured to said cam having one end thereof normally supported by a strand being advanced for entering one of said notches whenever said strand fails to support the end of said lever.

3. In an apparatus for knitting strands upon conductors, a plurality of cop-holders, a knitting head including a plurality of knitting needles serving to withdraw textile strands from cops held by said cop-holders and form a knitted covering over a conductor, means for advancing a conductor through said knitting head, and means for controlling the operation of said knit-

ting head and said advancing means comprising a switch, a shaft having a passage therethrough, a cam having a lobe formed thereon secured to the end of the shaft, a disc having notches formed in the periphery thereof rotatably mounted upon the shaft, means for oscillating the disc with respect to the shaft, a plurality of L-shaped dogs pivotally mounted on the shaft, and a plurality of grooved rollers secured upon the ends of the dogs for engaging strands being withdrawn from the cops to hold the dogs out of notches in the disc when the slack in the strands is below a predetermined amount, said dogs being designed to engage the notches in the disc to rotate the shaft and the cam thereon to open the switch and stop said knitting head and said advancing means whenever the slack in the strands exceeds said predetermined amount.

4. In an apparatus for knitting strands upon conductors, a plurality of cop-holders, a knitting head including a plurality of knitting needles serving to withdraw a plurality of textile strands from a plurality of cops held by said cop-holders and to form a knitted covering over a conductor, means for advancing such a conductor through said knitting head, and means for controlling the operation of said knitting head and said advancing means comprising a shaft aligned with the knitting head and having a passage through which a conductor to be covered may be drawn, a switch for deenergizing the knitting head when the contacts thereof are opened, a cam mounted on said shaft for opening the contacts of said switch, a disc having a plurality of radial notches formed therein rotatably mounted on said shaft, a plurality of L-shaped arms pivotally secured to said shaft around the periphery thereof, one end of each of said arms being designed to engage a strand being drawn to said knitting head, whereby the other end of each of said arms is held out of engagement with said disc when the slack in the strand remains below a predetermined amount, each of said arms falling into one of said notches when the slack in a strand engaged by that arm is greater than said predetermined amount so that the shaft and the disc become positively interlocked, and means for oscillating said disc to oscillate said shaft and said cam on the occurrence of such an interlocking between the shaft and the disc, whereby the contacts of said switch are opened by the cam.

JULIUS A. WAGNER.
